US00D769098S

(12) **United States Design Patent** (10) **Patent No.:** **US D769,098 S**
Huttunen (45) **Date of Patent:** **** Oct. 18, 2016**

(54) **AXE**

(71) Applicant: **Fiskars Garden Oy Ab**, Billnäs (FI)

(72) Inventor: **Aaro Huttunen**, Billnäs (FI)

(73) Assignee: **Fiskars Garden Oy Ab**, Billnäs (FI)

(**) Term: **14 Years**

(21) Appl. No.: **29/521,099**

(22) Filed: **Mar. 19, 2015**

(30) **Foreign Application Priority Data**

Sep. 22, 2014 (EM) 002542365-0006
Sep. 22, 2014 (EM) 002542365-0007

(51) **LOC (10) Cl.** **08-02**

(52) **U.S. Cl.**

USPC **D8/76**

(58) **Field of Classification Search**

(57) **CLAIM**

I claim the ornamental design for an axe, as shown and described.

DESCRIPTION

FIG. 1 is a front view of an embodiment the claimed design; FIG. 2 is a left side view of the claimed design of FIG. 1; FIG. 3 is a right side view of the claimed design of FIG. 1; FIG. 4 is a bottom view of the claimed design of FIG. 1; FIG. 5 is a right, rear, upper perspective view of the claimed design of FIG. 1; FIG. 6 is a right, front, lower perspective view of the claimed design of FIG. 1; FIG. 7 is a left, rear, lower perspective view of the claimed design of FIG. 1; FIG. 8 is a front view of another embodiment of the claimed design; FIG. 9 is a left side view of the claimed design of FIG. 8; FIG. 10 is a right side view of the claimed design of FIG. 8; FIG. 11 is a bottom view of the claimed design of FIG. 8; FIG. 12 is a right, rear, upper perspective view of the claimed design of FIG. 8; FIG. 13 is a right, front, lower perspective view of the claimed design of FIG. 8; and, FIG. 14 is a left, rear, lower perspective view of the claimed design of FIG. 8. Areas of the drawings shown in broken lines are directed to features of the axe that form no part of the claim.

1 Claim, 14 Drawing Sheets
